UNITED STATES PATENT OFFICE.

HARRY IRWIN JEFFERS, OF LEXINGTON, MISSISSIPPI, ASSIGNOR OF ONE-HALF TO SAMUEL D. GIVIN, OF SAME PLACE.

RAILWAY-TIE.

SPECIFICATION forming part of Letters Patent No. 445,275, dated January 27, 1891.

Application filed August 23, 1890. Serial No. 362,853. (No model.)

To all whom it may concern:

Be it known that I, HARRY IRWIN JEFFERS, a citizen of the United States, residing at Lexington, in the county of Holmes and State 5 of Mississippi, have invented new and useful Improvements in Railway-Ties, of which the following is a specification.

My invention relates to an improvement in railway-ties; and it consists in the construction and arrangement of parts hereinafter described, and definitely pointed out in the claims.

The object of my invention is to provide a simple, cheap, and durable tie having a 15 metallic base, and suitable means for securing the rails in place with but little trouble and expense. I obtain this object by the construction shown in the accompanying drawings, forming part of my specification, wherein 20 like letters of reference indicate corresponding parts in the several views, in which—

Figure 1 is a perspective view of a tie embodying my invention, with the rails shown in dotted lines, and Fig. 2 is a longitudinal 25 section taken through one end of the tie.

In the drawings, A represents a metallic tie formed with upwardly and inwardly inclined sides B and flat bottom C.

In the end portions of the sides of the tie, 30 in their upper edges, are formed grooves or recesses D, having vertical inner walls, horizontal bottoms, and inclined extensions at their forward ends, forming overlapping tongues d. These grooves are arranged directly opposite each other at their respective ends.

E represents binding-blocks formed with inwardly-inclined sides, arranged to be dovetailed into the tie, where they are permitted 40 a longitudinal movement only. The inner upper portions of the blocks are increased in size and have forwardly-inclined retaining tongues or extensions e, which are arranged on a plane with the tongues d of the tie.

45 Seated in a recess formed in the upper face of the block, at a point intermediate the grooves in the tie, are rubber or other elastic cushions F, on which the rails rest when locked in the tie. Directly in the rear of 50 the blocks I preferably cut the metal of the sides, and when the blocks are adjusted bend

the metal down, as at H, directly back of the blocks, thereby forming a key or retaining-prong to prevent the blocks from moving.

The operation of securing the rail is as follows: The blocks are first inserted and the tongues e forced back of the grooves. The rails are then placed in the grooves and the blocks forced forward, forcing the lower outer flange of the rail beneath the tongue d and 60 the tongue e projecting over the inner flange of the rail. The cut is then made in the side of the tie and the metal bent down, thus securely locking the blocks in place and securing the rails in the ties. It is evident that 65 the sides may be bent down on both sides of the tie, if desired; but I have found that the bending of one side only is generally sufficient.

I am aware that many minor changes in 70 the construction and arrangement of the parts of my device can be made and substituted for those herein shown and described without in the least departing from the nature and principle of my invention.

Having thus described my invention, what I 75 claim as new, and desire to secure by Letters Patent, is—

1. As a new article of manufacture, a metal railway-tie consisting of a metal base having inclined sides, blocks dovetailed in the same, and a bent-in portion in the rear of the blocks for retaining the same in place, substantially as described.

2. In a metal railway-tie, the combination, 85 with the base having inclined sides with grooves therein and retaining-tongues, of blocks in the tie having retaining-tongues opposite said other tongues, and a bent-down portion of the tie in the rear of the blocks, 90 substantially as described.

3. In a railway-tie, a sliding block dovetailed therein, a cushion on the blocks, tongues on the tie and blocks, and a bent-down retaining-point on the tie in the rear of the 95 blocks, substantially as described.

In testimony whereof I affix my signature in presence of two witnesses.

HARRY IRWIN JEFFERS.

Correction in Letters Patent No. 445,275.

It is hereby certified that the name of the assignee in Letters Patent No. 445,275, granted January 27, 1891, upon the application of Harry Irwin Jeffers, of Lexington, Mississippi, for an improvement in "Railway-Ties," was erroneously written and printed "Samuel D. Givin," whereas said name should have been written and printed *Samuel D. Gwin*; and that the said Letters Patent should be read with this correction therein that the same may conform to the record of the case in the Patent Office.

Signed, countersigned, and sealed this 17th day of February, A. D. 1891.

[SEAL.]

CYRUS BUSSEY,
Assistant Secretary of the Interior.

Countersigned:

C. E. MITCHELL,
Commissioner of Patents.
